Primary Examiner — Susan Moon Lee

(57) **CLAIM**

The ornamental design for a combined cat litter scoop holder and scoop, as shown and described.

DESCRIPTION

FIG. 1 is a perspective view of a cat litter scoop holder of a combined cat litter scoop holder and scoop showing my new design, shown separately for ease of illustration; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of a cat litter scoop of the combined cat litter scoop holder and scoop, shown separately for ease of illustration; FIG. 10 is another perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; and, FIG. 17 is a perspective view of the combined cat litter scoop holder and scoop, where the cat litter scoop is assembled with the cat litter scoop holder. The broken lines in the drawings depict portions of the combined cat litter scoop holder and scoop that form no part of the claimed design.
